UNITED STATES PATENT OFFICE.

FRANK BATOVEC, SR., OF NEW YORK, N. Y., ASSIGNOR TO FRANK BATOVEC, JR., OF NEW YORK, N. Y.

BUTTON.

Application filed May 9, 1927. Serial No. 190,054

This invention relates to improvements in buttons.

The primary object of the invention resides in a button constructed of pearl, bone or other fragile material and which type of buttons are commonly used on garments but which are likely to become damaged during the passage of the garment through a washing machine or when passing a flat iron over the button during the ironing of the garment. It is my intention to provide a protecting shell member for the button to prevent breakage of the same during laundering of a garment to which the bottom may be attached.

Another object of the invention is to provide a button which includes a center piece of fragile material such as pearl or bone and which is received in a shell member or casing by crimping the peripheral edge of the casing over the top outer edge of the center piece so that the outer face of the center piece is disposed on a plane even or below the peripheral edge of the shell member whereby the edge of the shell member serves as a guard for the center piece to protect the same against contact with an iron or the like.

A further object of the invention is to provide a button having an ornamental center piece mounted within an outer casing or shell member and which is simple and inexpensive of manufacture and strong and durable for the purpose intended.

With these and other objects in view, the invention resides in certain novel construction and combination and arrangement of parts, the essential features of which are hereinafter fully described, are particularly pointed out in the appended claim, and are illustrated in the accompanying drawing, in which:

Figure 1 is a perspective view of my improved button.

Figure 2 is a top plan view of the same.

Figure 3 is a vertical sectional view on the line 3—3 of Figure 2.

Figure 4 is a bottom plan view.

Figure 5 is a vertical sectional view through a slightly modified form.

Figure 6 is a bottom plan view of the form shown in Figure 5.

Referring more particularly to the drawing, the reference numeral 10 designates my improved button in its entirety and which

includes a center filling piece 11 and an outer 55 protecting shell member or casing 12.

The filling piece 11 is constructed of pearl or bone and may have any suitable design or ornamentation on the outer face thereof. In the drawing, I have shown the filling piece 60 in the form of a disk but the same may be of any configuration if desired. The top face of the filling piece 11 is provided with a reduced annular flange 13, and a concave recess 14 provided in its outer face and with 65 which openings 15 communicate and which openings lead to the under face of the filling piece.

The shell member 12 hereinbefore mentioned is constructed of light metal and comprises a bottom wall 16 and an annular side wall 17 of a size to snugly receive the filling piece 11. The peripheral edge of the side wall is crimped over the flange 13 of the filling piece after the latter has been set in place 70 to provide a retaining bead 18. The bead 18 is disposed at a plane either flush with the top of the filling piece or slightly above the same, so that an iron or the like when passed over the button will be supported by the bead 75 80 18 to relieve the weight of the iron from the fragile center piece 11. The bottom 16 of the shell member is provided with openings 19 for register with the openings 15 to permit 85 of the passage of the stitching when the button is sewed to a garment. The stitching seats in the concave recess 14 to lie below the top plan of the button.

In Figures 5 and 6 of the drawing, I have shown a slightly modified form of button 90 which may be used when it is desired that the stitching be concealed and that the button should project slightly from the fabric to which it is attached. In this form, the numeral 11' designates the filling piece and 95 12' the shell member and which filling piece is secured to the shell member in the manner already described. The bottom of the shell member is bulged outwardly as at 16' and is provided with opposed openings 19' 100 through which the stitching passes for securing the button to the fabric of a garment. It will be seen that the back of the button conceals the stitching and the bulged portion 16' serves to space the button from the fabric 105 to receive the thickness of the fabric which is passed over the button.

While I have described what I deem to be

the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claim.

What is claimed as new is:—

- 10 A button comprising a center piece having a recess in one face thereof, a shell member

formed from a single piece of material having a bottom disc, said center piece and bottom disc having aligned holes therein, the holes in said center piece opening into said recess, and a peripheral flange vertical to said disc, the top of said flange being above said recessed face.

In testimony whereof I have affixed my signature.

FRANK BATOVEC, Sr.
